UNITED STATES PATENT OFFICE.

JAMES A. MILLIKEN, OF BIDDEFORD, MAINE, ASSIGNOR OF ONE-HALF TO
HARRY H. HASEY, OF SAME PLACE.

HEATING-STOVE.

SPECIFICATION forming part of Letters Patent No. 249,854, dated November 22, 1881.

Application filed July 29, 1881. (No model.)

To all whom it may concern:

Be it known that I, JAMES A. MILLIKEN, of Biddeford, York county, State of Maine, have invented an Improvement in Heating-Stoves, 5 of which the following description, in connection with the accompanying drawings, is a specification.

This invention has for its object the production of an economical heating-stove provided 10 with chambers for warming cool air and discharging it again into the room. The products of combustion, instead of passing directly into a pipe and to the chimney, are made to pass down through the lower part or base 15 of the stove, from whence they rise into the pipe leading to the chimney.

Figure 1 represents, in side elevation and partial section, a stove embodying my invention; Fig. 2, a partial vertical cross-section of 20 the base on dotted line $x-x$; Fig. 3, a horizontal section of the base, showing the main central and side flues; and Fig. 4 is a partial rear elevation, showing the outer plate forming the air-chamber c^4 .

25 The cylinder or drum a , provided with any usual or suitable lining and grate, is extended above the enlarged ash-pit portion b , which receives the ash-pan and ashes. Somewhat below the floor-plate b^2 of the ash-pit portion b , I 30 have made a floor-plate, d , which I have divided by partitions $g h i$, so as to form a series of flues, $e e' e^2$, and an air-space, c , the latter being between the bottom of the ash-pit portion and the top of the plates $g h i$, herein shown 35 as arched. (See Fig. 2.) The flue e is in communication at its rear with the downflue l in the pipe t , so that when the damper m is up, as in full lines, Fig. 1, the products of combustion pass down the flue l , along flue e , out from 40 its front end into the flues e' and e^2 to the back of the base of the stove, thence up the rising-flue n , and out at n^2 into any suitable pipe leading into the chimney. During such passage of the products of combustion the said products act to heat the air in the air-chamber c , 45 fed by cold air at the openings c^2 , and such heated air rises into the space c^1 , from which

it flows into the room through the register-spaces c^5 . (See Figs. 1 and 4.) So, also, the products of combustion heat the air which rises 50 in the air-pipe space p , permitting the discharge of air therefrom through the opening p' (see Fig. 1) into the room. When the fire is first started the damper m will be turned down, as in dotted lines, and then the products of combustion will pass through a hole in the division-plate r and out at exit n^2 . 55

A stove constructed as described will throw off a large amount of heat in proportion to the fuel consumed, and will in its air-chamber c 60 and pipe p warm a great quantity of external air and project it upward and outward into the room, and the products of combustion leaving the stove at the exit-opening n^2 will have substantially all their heat abstracted. 65

I claim—

1. A heating-stove composed of a cylinder, a , an ash-pit portion below the said cylinder, a base below and separated from the ash-pit by a plate, said base containing an air-chamber, c , an outlet for air heated in said chamber, and smoke-flues $e e' e^2$, and a divided pipe, t , leading by one division from the cylinder to the base smoke-flues, and thence by the other division to the chimney, the whole combined 70 and arranged to operate substantially as specified. 75

2. The cylinder a , ash-pit portion b , base portion composed of side pieces, floor-plates $b^2 d$, partitions therein, arranged as described, 80 to form an air-chamber, c , and flues $e e' e^2$, combined with the air-space c^1 at the rear of the ash-pit portion b , the air-chamber c being provided with openings for the reception of air, and the chamber c^1 with other openings for the 85 discharge of heated air from the chamber c , substantially as described.

In testimony whereof I have signed my name to this specification in the presence of two subscribing witnesses.

JAMES A. MILLIKEN.
